UNITED STATES PATENT OFFICE.

WILLIAM H. THURBER, OF PROVIDENCE, RHODE ISLAND.

DESIGN FOR A POCKET-BOOK.

SPECIFICATION forming part of Design No. 30,831, dated May 23, 1899.

Application filed April 12, 1899. Serial No. 712,806. Term of patent 7 years.

To all whom it may concern:

Be it known that I, WILLIAM H. THURBER, of Providence, in the county of Providence and State of Rhode Island, have invented and produced a new and original Design for a Pocket-Book, of which the following is a specification, reference being had to the accompanying drawings, forming part thereof.

Figure 1 is a front view of a pocket-book; and Fig. 2, a rear view of the same, showing my design.

The leading feature of my design consists in the outline of the pocket-book, in which the upper edge connects with the two side margins at right angles, the lower edge connecting with the side by curved lines, forming rounded corners. A marginal bead extends along the two sides, and in the panel are placed raised symbols indicating the United States Government, consisting in the conventional representation of a female head surrounded with stars, and an eagle with extended wings and talons, surmounted with a group of stars on the front and rear of the pocket-book, as will be more fully described hereinafter.

In the drawings, *a* indicates the front panel of approximately rectangular shape with the lower corners rounded; *b*, the front of the body of the pocket-book of approximately rectangular shape. The panel *a* has near its

center the raised female head *c*; resembling the conventional representation of the head of the Goddess of Liberty. Thirteen symbolic representations of stars *d* surround the head *c*, and below the head the ribbon-scroll *e* extends. On the rear surface of the pocket-book the panel *f* is ornamented by the raised representation *g* of an eagle with outstretched wings and with feet, from one of which extends the foliated branch *h*, resembling an olive-branch, and from the other the bunch of arrows *i*. The shield *j* extends across the center of the eagle *g*. A group of stars *k* above the head of the eagle are arranged between the ribbon-scroll *l*.

The panels *a* and *f*, as also the body of the pocket-book, have the rounded corners *m*, and the upper rectangular portion has the roll edge *n*.

Having thus described my invention, what I claim as new, and desire to secure by Letters Patent, is—

The design for a pocket-book substantially as herein shown and described.

In witness whereof I have hereunto set my hand.

WILLIAM H. THURBER.
